UNITED STATES PATENT OFFICE.

SOLON S. STANLEY, OF SANDUSKY, OHIO.

IMPROVEMENT IN CORNER-POSTS FOR CARRIAGE-SEATS.

Specification forming part of Letters Patent No. 123,302, dated January 30, 1872.

To all whom it may concern:

Be it known that I, SOLON S. STANLEY, of Sandusky, in the county of Erie, State of Ohio, have invented certain new and useful Improvements in Corner-Posts for Carriage-Seats, of which the following is a full and complete description, reference being had to the accompanying drawing making a part of this specification, in which—

Figure 1 is a side view of the standard; Fig. 2, a view of the rear side. Fig. 3 is a top view.

Like letters of reference refer to like parts in the several views.

The nature of this invention relates to a corner post or standard for carriage-seats; and the object thereof is to provide a neat and substantial support to the back rail and arms of the seat.

Said post is made of iron, and consists in part of a shank, A, having a foot piece, B, whereby it is screwed or otherwise fastened to the bottom of the seat in the position shown in Fig. 1. The upper end of the post is provided with an angle-iron, C, consisting of thin plates or wings, to which the ends of the rails D and ends of the arms E are fastened, as shown in the drawing, in which it will be seen that the rail and arms are secured to the inside of the angle-iron, the iron being let into the wood flush therewith and thereto secured by screws F.

It will be observed that the ends of the angle-iron are cut to a miter angle, so that the ends fit in the wood in a dovetail-like manner, as shown at a, Fig. 5, which assists in holding the rail to the iron, thereby making the corner

much stronger than if let in the wood with a square end, but which the end of the wings may have if so desired, as indicated by the dotted lines b, Fig. 3.

I am aware that iron posts or standards have been used for corner-posts for carriage-seats; but such posts have a socket or sockets in which to insert the ends of the back rail and arms; but this I do not claim, as my post differs from that in having no socket, but an angle-iron, provided with a miter end or ends, so that they are fitted to the rail in a dovetail-like manner.

By thus using an angle-iron instead of a socket for holding the ends of the back rail and arms of the seat, I am enabled to cushion the inside and top of the rail and arms, and secure the trimmings to the corners by nails in the usual way, but which cannot be done when the corners are formed of iron sockets, as nails cannot be driven therein for fastening the trimmings.

Claim.

What I claim as my invention, and desire to secure by Letters Patent, is—

The herein-described corner-posts A for wagon and carriage seats, provided with an angle-iron, C, to which is attached the back rail and arms of the seat, forming an angular joint, in the manner substantially as described, and for the purpose set forth.

SOLON S. STANLEY.
